UNITED STATES PATENT OFFICE.

MAX HOGE AND PAUL C. RIEBE, OF CHICAGO, ILLINOIS, ASSIGNEES, BY DIRECT AND MESNE ASSIGNMENTS, TO UPRIGHT GRAIN PRINTING BASE COMPANY, OF CHICAGO, ILLINOIS, A CORPORATION OF ILLINOIS.

BASE FOR PRINTING-PLATES.

1,028,821.

Specification of Letters Patent.

Patented June 4, 1912.

Original application filed February 8, 1909, Serial No. 476,841. Divided and this application filed May 10, 1909. Serial No. 495,166.

To all whom it may concern.

Be it known that we, MAX HOGE and PAUL C. RIEBE, citizens of the United States, residing at Chicago, in the county of Cook 5 and State of Illinois, have invented new and useful Improvements in Bases for Printing Plates, of which the following is a specification, reference being had to the accompanying drawings, forming a part thereof.

10 This application is a division of our application Serial No. 476,841, filed February 8, 1909, the generic invention presented in that application consisting in the employment, for a printing base, of wood blocks 15 with the grain vertical, so that the printing plate is mounted on the end of the grain. The specific embodiment of that invention which is the subject matter of this divisional application consists in such wood blocks 20 with the grain vertical, assembled and united by intersecting septa of longitudinally tenacious material, and otherwise characterized as particularly set out in the claims.

25 In the drawings:—Figure 1 is a plan view of a base block for a printing plate embodying this invention. Fig. 2 is a section at the line 2—2 on Fig. 1. Fig. 3 is a plan view of a slightly modified form of the same 30 specific invention. Fig. 4 is a plan view of a modified form of the invention, showing wood septa inserted in a diagonal arrangement of the blocks.

In the drawings the unitary base shown 35 in Figs. 1 and 3 comprises a multiplicity of relatively small wood blocks, A, with the grain vertical, so that the base at the surface for mounting the printing plate presents the end of the grain of the wood. These blocks 40 are preferably rectangular and also preferably square, excepting those around the margin of the form shown in Fig. 3, which are triangular. The blocks are assembled side- 45 wise,—that is to say, so that the proximate surfaces of adjacent blocks present the side of the grain to each other, and are glued together. Preferably, in addition to the intersecting glue septa which result from thus assembling and gluing, and which have 50 the desired longitudinal tenacity, there are interposed between the blocks thin strips of wood, B, to constitute the intersecting septa, or, in lieu of wood, other fibrous ma-

terial of suitable tenacity, such septa being united by the glue to the blocks and being 55 let into each other at their intersections in a manner which requires no explanation.

In the form shown in Figs. 1 and 2 the blocks, A, are assembled in rows parallel to the sides of the entire base, and when properly made and well glued with the intersecting septa of wood or other longitudinally fibrous material, no encompassing band or frame is necessary, though it may 60 be employed as represented in Fig. 3. 65

In Figs. 3 and 4 the blocks, A, are represented as assembled in rows oblique to the sides of the entire base, thus requiring triangular half-square blocks, B¹, and quarter-square blocks, B², to complete the outline. 70 In Fig. 3 the blocks are represented as united only by the glue septa indicated by the heavy lines, b, intersecting and forming a substantially unitary skeleton of cells, each of which is occupied by a block. In 75 this figure the entire base is represented as inclosed in a binding or frame, C, which is preferably of wood or other suitably tenacious material united to the margin of the assembled blocks by glue in the same manner as the blocks are united to each other. 80

It will be understood that the septa of wood or other fibrous material, B, or the septa of glue only, b, may be employed in either arrangement of the blocks,—that is, 85 either that shown in Fig. 1, or that shown in Fig. 3, and Fig. 4 illustrates such combination of the wood septa with the diagonal arrangement of the blocks.

The advantage of the oblique arrangement of the blocks is illustrated in Fig. 3, consisting in that a printing plate, D, mounted upon the base and secured by tacks, d, in the customary manner can always be thus secured by tacks penetrating the end 95 of the grain of the blocks and without liability to strike the septa, which if of glue would be more difficult to penetrate, and if of wooden strips would be liable to be split by the penetration, which is not the case 100 with the end of the grain, as fully pointed out in our said application Serial No. 476,841.

We claim:

1. A base block for printing plates made 105 of a plurality of elements of wood with the

grain vertical and interposed intersecting septa of longitudinally fibrous material to which said elements are glued.

2. A base block for printing plates comprising, in combination with a rectangular peripheral band or frame, a multiplicity of rectangular elements of wood with the grain vertical assembled in intersecting rows oblique to the sides of the frame; triangular elements occupying the marginal triangular spaces remaining between the oblique blocks and the encompassing frame, and in-

intersecting septa of longitudinally tenacious material uniting and united to the blocks.

In testimony whereof, we have hereunto set our hands, in the presence of two witnesses, at Chicago, Illinois, this 8th day of May, A. D. 1909.

MAX HOGE
PAUL C. RIEBE.

In the presence of—
M. GERTRUDE ADY,
JULIA S. ABBOTT.
